REFINING OF SHALE OIL

James R. Smith and Gerald U. Dinneen, Laramie,
Wyo., assignors to the United States of America
as represented by the Secretary of the Interior

Application August 31, 1950, Serial No. 182,528

9 Claims. (Cl. 196—147)

(Granted under the act of March 3, 1883, as
amended April 30, 1928; 370 O. G. 757)

1

The invention herein described and claimed may be manufactured and used by or for the Government of the United States of America for governmental purposes without the payment of royalties thereon or therefor.

This invention relates to the refining of crude oils derived from oil shale and is particularly concerned with a method for the removal of organic nitrogen compounds from shale oils wherein these compounds normally occur in large amounts.

The term shale oil, as commonly used in the United States, and as employed herein, refers to a mixture of hydrocarbons and certain nitrogen, sulfur, and oxygen compounds obtained usually by destructive distillation of sedimentary rocks containing kerogen, commonly termed oil shales. Deposits of oil shale of varying extent and richness are found in this country, and in many parts of the world. Of the domestic deposits, the richest known are those found in the so-called Green River formation situated principally in Colorado, Wyoming, and Utah.

In the handling and refining of crude shale oil one of the main problems encountered has been the occurrence of large percentages of organic nitrogen compounds in the crude distillate. A typical crude prepared from Colorado shale, for example, although containing only from 1 to 2% nitrogen by weight, will contain in some of the higher boiling fractions from 30 to 50% of nitrogen compounds. These nitrogen compounds, which are largely heterocyclics, seriously effect the stability of any type of fuel that may be made from the crude and therefore must be removed to produce a commercially acceptable product. During refining, the presence of these nitrogen compounds is a serious disadvantage since the shale oil nitrogen compounds act as poisons to catalytic cracking catalysts and thus prevent the application of the catalytic cracking technique for the conversion of the heavy crudes into lighter diesel and gasoline fractions. The presence of large amounts of nitrogen compounds furthermore gives the oil an extremely dark color and renders analysis of the crudes very difficult.

Several methods have been previously proposed for removal of these nitrogen compounds. For example, it is possible to effect their removal from various fractions of the crude by acid treatment but this method results in a loss of from 20 to 40% in the acid sludge. High pressure hydrogenation of the crude at from 6000 to 10,000 lbs. per square inch has also been proposed, but this method requires the use of expensive hydrogen and complicated high pressure equipment.

2

According to the present invention a method has been discovered for removing the organic nitrogen compounds present in shale oil by a relatively simple adsorption technique by which it is possible to make a clean cut separation between the hydrocarbons and the substantial amounts of nitrogen compounds present in the crude. By means of the method of the invention, the shale oil is separated into two separate fractions, one containing substantially all the hydrocarbons present in the crude oil, including the paraffins, naphthenes, olefins, and aromatics, and the other fraction containing substantially all the nitrogen compounds present. The invention is based upon the discovery that, in contrast to other adsorbent materials, an adsorbent comprised essentially of magnesium silicate will strongly adsorb the type of nitrogen compounds found in shale oil, while at the same time will have substantially no affinity for the type of hydrocarbons, including the high percentage of olefins and aromatics, found in crude shale distillates. The high selectivity and the large adsorbent capacity of magnesium silicate adsorbents permits a substantially quantitative removal of nitrogen compounds which are present in amounts ranging from 10 to 60% by weight depending on the fraction under consideration. Further advantages of a magnesium silicate adsorbent is the ease with which the large amounts of adsorbed nitrogen compounds may be removed from the adsorbent and recovered with substantially no loss, and the ease with which the adsorbent may be regenerated for further use. Other known adsorbents, commonly used in the petroleum industry and for other purposes, such as silica gel, alumina, fuller's earth, activated bauxite and activated carbon are unsuited for the removal of nitrogen compounds in the amounts in which they are present in most crude shale oils.

Broadly the method of the invention involves contacting the shale oil, containing substantial amounts of nitrogen compounds, with an adsorbent comprised essentially of magnesium silicate, the contacting being accomplished preferably by percolating the nitrogen containing shale oil through a tower containing the adsorbent, to thereby adsorb the major portion of the organic nitrogen compounds on the magnesium silicate. The nonadsorbed portion of the shale oil, consisting essentially of hydrocarbons, is then recovered, most desirably by washing the adsorbent with an essentially nonpolar eluting agent which causes substantially no desorption of nitrogen compounds. Following the recovery of the

hydrocarbons, the nitrogen compounds may be separately recovered by contacting the adsorbent with a polar desorbing agent which is more strongly adsorbed than the nitrogen compounds, and which thus causes substantially complete displacement of the nitrogen compounds from the adsorbent. After removal of the desorbing agent and after regeneration by steaming and drying, for example, the magnesium silicate adsorbent is ready for reuse.

Examples

The following examples illustrate the application of the invention to the separation and separate recovery of the nitrogen and hydrocarbon compounds present in several crude oil distillation fractions of increasing molecular weight and increasing percentage of nitrogen compounds. In each case, the crude shale oil from which the distillation fraction was prepared was produced by the so-called N-T-U retorting process from a Colorado oil shale yielding an average of 30 gallons of crude oil per ton of shale. According to the N-T-U process, a cylindrical retort is filled with crushed shale. The shale at the top of the retort is ignited and air is blown downwardly through the bed of shale. Heat furnished by combustion of the upper layer of shale serves to decompose kerogen in the layers of shale beneath the combustion zone. The oil vapors which distill from the shale are carried out of the retort in the hot air stream. The combustion zone advances downwardly through the complete charge in the cylindrical retort, residual carbon in the shale from which the oil has already been driven supporting combustion and furnishing heat throughout the retorting process. Distillation temperatures are in the neighborhood of from 850° to 1000° F. From this crude, four distillation fractions were prepared: a naphtha fraction boiling between 155-415° F., a kerosene fraction boiling between 400-585° F., a light gas oil fraction boiling between 570-750° F., and a heavy gas

are solids, or very viscous at room temperature were diluted with n-pentane to prevent solidification of the material in the adsorbent.

In each case, after the sample had entered the adsorbent, n-pentane was added at the top of the column, allowed to percolate therethrough, and the pentane and the portion of the sample eluted from the adsorbent were collected in a receiver as they emerged from the column. Percolation of pentane through the column was continued until the composition of the material issuing from the bottom of the column approached closely to that of pure pentane as indicated by the refractive index thereof. Approximately two liters of pentane per 100 grams of sample were required to give complete elution.

Following the pentane elution a fresh receiver was introduced under the column and methanol was then introduced at the top of the column and allowed to percolate down through the adsorbent. The methanol, being more strongly adsorbed on the magnesium silicate than the nitrogen compounds, displaced the nitrogen compounds and these were collected in the fresh receiver at the bottom of the column. Percolation of methanol through the column was continued until substantially pure methanol issued from the bottom of the column, approximately 1.2 liters of methanol being required for the desorption of 100 grams of sample.

The pentane eluted fraction, containing the bulk of the hydrocarbons with small amounts of nitrogen compounds, and the methanol desorbed fraction, containing substantially all the nitrogen compounds present in the original sample, were then stripped respectively of pentane and methanol and the composition of each fraction determined.

In the table below are tabulated the results obtained by the procedure outlined above, giving the percent of nitrogen and the percent of nitrogen compounds in the original sample, in the pentane eluted fraction, and in the methanol desorbed fraction, respectively.

Ex- ample	Fraction	Average mo- lecular weight of compounds in sample	Nitrogen weight per- cent in sample	Nitrogen compounds weight per- cent in sam- ple	Nitrogen compounds weight per- cent in pen- tane eluted fraction	Nitrogen compounds weight per- cent in pen- tane eluted fraction	Nitrogen weight per- cent in meth- anol desorbed fraction	Nitrogen compounds weight per- cent in meth- anol desorbed fraction
1.....	Heavy gas oil boiling over 625° F.							
2.....	Light gas oil boiling range 570-750° F.	320	1.78	40.8	0.11	2.5	3.73	85.4
3.....	Kerosine boiling range 400- 585° F.	280	1.82	36.4	0.13	2.6	4.34	86.8

oil fraction boiling above 625° F.

A weighed sample of each of the four fractions mentioned above was allowed to percolate down through a column packed with a granulated magnesium silicate adsorbent. The adsorbent used was prepared generally according to the process described in U. S. Patent 2,393,625 to Simons, except that the activation step described in this patent, accomplished by drying the precipitated magnesium silicate gel at an elevated temperature up to 1300° F., was omitted, the precipitated gel merely being air dried. This adsorbent was employed in a particle size of from 30 to 60 mesh, and was packed in a column having a height to diameter ratio of about 40. The weight of adsorbent employed in each case was equal to 300 times the weight of nitrogen in the sample. The heavy gas oil and the light gas oil fractions which

It will be noted that in each case well over 90 percent of the nitrogen compounds in the original sample are concentrated in the methanol desorbed fraction. Further analysis of the nitrogen high fraction indicated the presence of approximately 4 to 7 percent sulfur compounds and also some oxygen-containing heterocyclics, little if any hydrocarbons being present. The pentane eluted fraction, on the other hand, contained a small percentage of nitrogen compounds, from 4 to 7 percent sulfur compounds, the bulk of this fraction being hydrocarbons, including paraffins, naphthenes, olefins, and aromatics.

The magnesium silicate adsorbent employed is preferably a synthetically prepared precipitated magnesium silicate gel although any synthetic or natural magnesium silicate having suitable physical properties (e. g. hardness and

porosity) may be employed. The hydrated gel, after precipitation, may be activated, if desired, by rapid drying at an elevated temperature, but preferably the hydrated precipitated gel is not subjected to an activating treatment but is merely air dried. Although activation by rapid drying at an elevated temperature increases the adsorption capacity of the gel for nitrogen compounds, the activation causes an even greater increase in its adsorption capacity for some nonnitrogen-containing compounds, such as naphthalene and its homologs and other condensed ring aromatic hydrocarbons, in certain shale oil fractions. Consequently, for more clean cut separations, an unactivated air dried magnesium silicate adsorbent is employed.

The ratio of adsorbent to the shale oil being treated necessary to provide efficient separation of the nitrogen compounds and hydrocarbons will vary somewhat according to the manner of preparation of the magnesium silicate adsorbent and with the type of shale oil fraction being processed. In general, an amount by weight of magnesium silicate adsorbent equal to from 300 to 500 times the weight of nitrogen in the shale oil to be processed is required.

After desorption of the nitrogen compounds, and elimination of the bulk of the desorbent by sweeping with a hot gas for example, the adsorbent will usually retain a certain amount of impurities consisting chiefly of an unidentified type of nitrogen compound and possibly oxygen compounds. To regenerate the adsorbent for reuse it is not necessary or desirable to burn off these impurities. A steam purge at a temperature between 290 and 310° F. followed by air drying will ordinarily suffice to render the adsorbent fit for reuse.

The method of the invention may be carried out according to any of the usual adsorption techniques but is preferably conducted according to the so-called percolation filtration technique in which the shale oil to be processed is added to the top of a tower packed with the adsorbent and allowed to percolate down through the adsorbent, the nonadsorbed material being collected at the bottom of the column. This technique lends itself readily to the elution and desorption steps, the eluting and desorbing agents likewise being percolated down through the tower to remove the nonadsorbed hydrocarbons and the adsorbed nitrogen compounds respectively. Since decreasing the particle size of the adsorbent usually will increase its adsorption capacity but will decrease the percolation rate, in the application of the percolation technique, an adsorbent particle size should be chosen which offers a satisfactory compromise between these two factors. On the basis of these considerations, particle sizes ranging from 10 to 100 mesh may be satisfactorily employed. The ratio of height to diameter of the packed column is preferably at least 30 but may range between 12 and 150.

As eluting agents for washing the nonadsorbed hydrocarbon portion of the shale oil from the magnesium silicate adsorbent, any essentially nonpolar organic solvent which causes substantially no desorption of the nitrogen compounds from the adsorbent may be employed. The most satisfactory eluents are saturated hydrocarbons, particularly those of the paraffin series. Aromatics and olefins are, in general, not desirable since they are more strongly adsorbed on the magnesium silicate adsorbent and consequently

cause greater desorption of nitrogen compounds. The eluent should have a boiling range such that it can be easily stripped by distillation from the eluted shale oil hydrocarbons. Thus, depending on the boiling range of the shale oil fraction, the eluent may have a boiling range as high as 250° to 300° F. However, eluents having a boiling range in the vicinity of 100° F. are more generally suitable. Examples of particular satisfactory eluents are the normal or iso-pentanes, hexanes, heptanes, and octanes, or any mixture of these, such as a saturated petroleum cut having a boiling range in the vicinity of the boiling range of these compounds.

As desorbing agents for desorbing the nitrogen compounds from the magnesium silicates adsorbent, organic solvents which are miscible with the nitrogen compounds in the shale oil, which have distinctly polar properties and which effect substantially complete displacement of nitrogen compounds from the adsorbent may be employed. It is essential of course, that the desorbing agent be more strongly adsorbed on the magnesium silicate adsorbent than the nitrogen compounds present in shale oil. The desorbent should have a boiling range below about 300° F. so that it can be easily handled and easily stripped from the desorbed nitrogen compounds. Low boiling alcohols, particularly the aliphatic alcohols, such as methyl, ethyl, n-propyl and iso-propyl are examples of particularly suitable desorbents.

The method of the invention is applicable to all types of shale oil which contain appreciable amounts of organic nitrogen compounds and is particularly useful in respect to shale oils which contain over 10% by weight of nitrogen compounds because of the difficulties inherent in the separation and separate recovery of these compounds in such large amounts when in intimate admixture with hydrocarbons of similar structure. The type and the amount of nitrogen compounds present in a particular shale oil will vary somewhat according to the type of oil shale from which it was produced, the method of retorting, and the type of refining operation, if any, to which it has been subjected. In general, the lower boiling shale oil fractions contain a smaller percentage of nitrogen and of nitrogen compounds than the higher boiling fractions. The invention has particular application to the type of shale oils derived by destructive distillation at temperatures from 700 to 1500° F. from oil shales found in the so-called Green River formation situated principally in Colorado, Wyoming, and Utah, which contain nitrogen compounds in amounts ranging from 5% in the lightest fractions of the crude to as high as 60% in the heavy fractions.

If desired, the method of the invention may be carried out strictly as a batch operation. However, when operating on a large scale it is preferable to maintain continuous charge and product flows in the operation of the percolation towers. Reference is now made to the accompanying drawing which diagrammatically illustrates the operation of the invention in this manner.

In the drawing, eleven adsorption towers are shown, bearing the reference numerals 1 to 11, respectively, although more or fewer may be employed. The process illustrated involves 5 stages, each stage involving the use of one or more towers. In the first stage (towers 1-11), separation of the nitrogen compounds from the hydrocarbons is accomplished by adsorption of the nitrogen compounds on the magnesium silicate

adsorbent followed by elution of the hydrocarbon compounds; in the second stage (tower 6) residual eluent is recovered by sweeping a stream of heated gas through the tower; in the third stage (towers 4 and 5) the nitrogen compounds are desorbed; in the fourth stage (tower 3) residual desorbent is removed by sweeping with a hot gas; and in the fifth stage (towers 1 and 2) the adsorbent is regenerated for reuse. The towers are transferred successively from one stage to another in the direction and order indicated by the arrows at the right of each adsorption column. After regeneration, the regenerated tower re-enters the process as the last tower in the separation stage. As shown in the drawing, for example, after regeneration, tower No. 1 will take over the functions of tower 11; tower 11 will take over the functions of tower 10; tower 10 will take over the functions of tower 9, and so forth. By a suitable system of manifolding and valve arrangement, shifting of the towers successively through the various stages of the process can be accomplished in such a manner that continuous charge and product flows are maintained.

As shown in the drawing, a shale oil fraction, which has not been processed for the removal of nitrogen compounds, is fed from storage tank 12 by line 13 into mixing tank 14 where it is mixed, if desired, with eluent from eluent storage tank 15. The oil-eluent mixture is fed by line 16 into the separation stage, flowing into tower 9 and percolating downwardly through towers 9, 10, and 11 where the nitrogen compounds are removed from the mixture by the magnesium silicate adsorbent. In towers 7 and 8 fresh eluent is supplied from eluent storage tank 15 by line 17 and percolates downwardly through these towers, to remove the hydrocarbons from adsorbent which has been previously saturated to capacity with nitrogen compounds. The eluent-hydrocarbon mixture flowing from the bottom of tower 8 is percolated through the remaining towers of the separation stage and the total eluent-hydrocarbon mixture from the separation stage is withdrawn from the last tower thereof by line 18 and conducted to a stripping unit 19. In the stripping unit 19, which may be, for example, a distillation column of suitable design, the hydrocarbon products are stripped of eluent and conducted by line 20 to hydrocarbon product storage tank 21, the eluent being conducted by line 22 to eluent storage tank 15.

In tower 6, the adsorbent, saturated with nitrogen compounds, but washed free of hydrocarbons, is stripped of residual eluent by a stream of heated air or other gas. The eluent, after being recovered from the gas stream in a suitable recovery unit 23 is then conducted to eluent storage 15.

In towers 4 and 5 nitrogen compounds are removed from the adsorbent by a suitable desorbing agent introduced from storage tank 24 by line 25. Desorbed nitrogen compounds and desorbent are conducted by line 26 to a suitable stripping unit 27 where the nitrogen compounds are separated from the desorbent and conducted by line 28 to storage tank 29. The desorbent is conducted to desorbent storage tank 24 by line 30 for reuse.

In tower 3 the residual desorbent remaining after desorption of the nitrogen compounds is stripped from the adsorbent by a stream of heated air. The air stream, containing desorbent is conducted to a recovery unit 31 where the desorbent is recovered and conducted to storage by line 32.

5 In tower 2, the adsorbent, previously stripped of desorbent, is regenerated by steam purging at a temperature of from 290 to 310° F. After drying in tower 1 the adsorbent is then ready to be returned to the process.

10 It is to be understood, of course, that when tower 9 becomes saturated to capacity with nitrogen compounds, the flow of oil charge to this tower is cut off, and by provision of the necessary piping connections (not shown) and by suitable shifting of valves, the flow of raw charge is transferred to tower 10; tower 9 taking over the functions of tower 8, tower 8 taking over the functions of tower 7, and so forth, each tower changing its 15 functions as previously explained.

20 The hydrocarbons recovered and stored in tank 21 are virtually free of nitrogen compounds and may be processed according to conventional petroleum techniques, including catalytic cracking techniques. The nitrogen-containing fraction, stored in tank 29 may be processed separately, for the removal of nitrogen compounds, for example, by high pressure hydrogenation, or put to any other desired use.

25 It is to be understood that the above description, together with the specific examples and embodiments described, is intended merely to illustrate the invention, and that the invention is not to be limited thereto, nor in any way except by the scope of the appended claims.

30 We claim:

1. A method for the separation of organic nitrogen compounds from shale oils containing said nitrogen compounds in amounts ranging from about 10% to 60% by weight and likewise containing substantial amounts of olefinic and aromatic hydrocarbons comprising the steps of contacting said shale oil with an adsorbent comprising magnesium silicate, adsorbing the major portion of said nitrogen compounds on said magnesium silicate adsorbent, and recovering the nonadsorbed portion of said shale oil.

45 2. A method for the separation of organic nitrogen compounds from shale oil containing said nitrogen compounds in amounts ranging from about 10% to 60% by weight and likewise containing substantial amounts of olefinic and aromatic hydrocarbons comprising the steps of contacting said shale oil with an adsorbent comprising magnesium silicate, adsorbing the major portion of said nitrogen compounds on said magnesium silicate adsorbent, and recovering the nonadsorbed portion of said shale oil by washing said adsorbent with an essentially nonpolar eluting agent causing substantially no desorption of said nitrogen compounds.

50 3. A method for the separation of organic nitrogen compounds from shale oils containing said nitrogen compounds in amounts ranging from about 10% to 60% by weight and likewise containing substantial amounts of olefinic and aromatic hydrocarbons comprising the steps of contacting said shale oil with an adsorbent comprising magnesium silicate, adsorbing the major portion of said nitrogen compounds on said magnesium silicate adsorbent, and recovering the nonadsorbed portion of said shale oil by washing said adsorbent with a nonpolar eluting agent comprising a saturated hydrocarbon.

55 4. A method for separately recovering hydrocarbons and organic nitrogen compounds from a shale oil containing said nitrogen compounds in amounts ranging from about 10% to 60% by weight and likewise containing substantial amounts of olefinic and aromatic hydrocarbons

comprising the steps of contacting said shale oil with an adsorbent comprising magnesium silicate, adsorbing the major portion of said nitrogen compounds on said magnesium silicate adsorbent, separately recovering the hydrocarbons present in said shale oil by washing said adsorbent with an essentially nonpolar eluting agent causing substantially no desorption of said nitrogen compounds, and then separately recovering said nitrogen compounds by contacting said adsorbent with a polar desorbing agent causing substantially complete displacement of said nitrogen compounds from said adsorbent.

5. A method for separately recovering hydrocarbons and organic nitrogen compounds from a shale oil containing said nitrogen compounds in amounts ranging from about 10% to 60% by weight and likewise containing substantial amounts of olefinic and aromatic hydrocarbons comprising the steps of contacting said shale oil with an adsorbent comprising magnesium silicate, adsorbing the major portion of said nitrogen compounds on said magnesium silicate adsorbent, separately recovering the hydrocarbons present in said shale oil by washing said adsorbent with an essentially nonpolar eluting agent comprising a saturated hydrocarbon, and then separately recovering said nitrogen compounds by contacting said adsorbent with a polar desorbing agent comprising an aliphatic alcohol.

6. A method for the separation of organic nitrogen compounds from shale oil containing said nitrogen compounds in amounts ranging from about 10% to 60% by weight and likewise containing substantial amounts of olefinic and aromatic hydrocarbons, comprising the steps of percolating said shale oil through a granular magnesium silicate adsorbent to thereby adsorb the major portion of said nitrogen compounds on said magnesium silicate adsorbent, and recovering the nonadsorbed portion of said shale oil by percolating an essentially nonpolar eluting agent through said adsorbent thereby to wash said nonadsorbed portion therefrom while causing substantially no desorption of said nitrogen compounds.

7. A method according to claim 5 wherein the nonpolar eluting agent comprises a saturated hydrocarbon.

8. A method for separately recovering hydrocarbons and organic nitrogen compounds from a shale oil containing said nitrogen compounds

in amounts ranging from about 10% to 60% by weight and likewise containing substantial amounts of olefinic and aromatic hydrocarbons comprising the steps of percolating said shale oil through a granular magnesium silicate adsorbent to thereby adsorb the major portion of said nitrogen compounds on said magnesium silicate adsorbent, separately recovering the hydrocarbons present in said shale oil by percolating an essentially nonpolar eluting agent through said adsorbent thereby to wash said hydrocarbons therefrom while causing substantially no desorption of said nitrogen compounds, and then separately recovering said nitrogen compounds by percolating a polar desorbing agent through said adsorbent thereby causing substantially complete displacement of said nitrogen compounds from said adsorbent.

9. A method for separately recovering hydrocarbons and organic nitrogen compounds from a shale oil containing said nitrogen compounds in amounts ranging from about 10% to 60% by weight and likewise containing substantial amounts of olefinic and aromatic hydrocarbons comprising the steps of percolating said shale oil through a granular magnesium silicate adsorbent to thereby adsorb the major portion of said nitrogen compounds on said magnesium silicate adsorbent, separately recovering the hydrocarbons present in said shale oil by percolating an essentially nonpolar eluting agent comprising a saturated hydrocarbon through said adsorbent, and then separately recovering said nitrogen compounds by percolating a polar desorbing agent comprising an aliphatic alcohol through said adsorbent.
